United States Patent Office.

EDWIN ALLEN, OF NORWICH, CONNECTICUT.

Letters Patent No. 70,773, dated November 12, 1867.

IMPROVEMENT IN PRINTING-PRESSES.

The Schedule referred to in these Letters Patent and making part of the same.

TO ALL WHOM IT MAY CONCERN:

Be it known that I, EDWIN ALLEN, of Norwich, in the county of New London, and State of Connecticut, have invented a certain new and useful Improvement on Printing-Presses, of which the following is a full, clear, and exact description, reference being had to the accompanying drawing, forming part of this specification, and in which—

Figure 1 represents a vertical section taken transversely through the form and impression-cylinders or devices.

Figure 2, a horizontal section, mainly through the dotted line $z z$ in fig. 1; and

Figure 3 a diagram, on an enlarged scale, in illustration of a mode of gearing the form and impression-cylinders or devices.

Similar letters of reference indicate corresponding parts.

The nature of my invention consists in a sliding arrangement of taper rolls used in setting up the inking-roller, whereby shrinkage of the latter is provided for, without change of rolls or adjustment in its bearings of the shaft which carries the same.

Referring to the accompanying drawing, which illustrates my invention in one at least of its forms or modes of putting it in practice, the press there exhibited, while it may be termed a cylinder-press, inasmuch as it embraces impression and form devices of a rotating character, differs from cylinder-presses generally in working a straight form, which difference constitutes a leading peculiarity of my invention.

A is the frame of the press, that may be constructed in any suitable manner; B, the table, over which the sheet is fed; and C the board over which it is delivered by, it may be, belt-conveyers D, provided with suitable cleats, *a*, and passing over or round pulleys E, motion being communicated to the same by any appropriate means. F is the rotating platen, hung on a shaft, *b*, carrying a spur-wheel, G, which gears with a spur-wheel, H, hung on a shaft, *c*, that carries the rotating bed, form, or type-carrier I. Thus geared, the bed and platen are made to rotate in unison, motion being given by any suitable means, and the wheels G and H being for the most part, say, of equal diameters, in order to bring the form and pressing or platen surfaces in proper relative position to produce an impression. These wheels, however, differ from ordinary spur-wheels in being, the one, H, made with its teeth of a straight-rack shape or form at portions of its periphery, and for lengths corresponding to the straight-form surfaces *d* of the rotating type-head I, while the other wheel G is, at corresponding parts, and for corresponding lengths or distances, of a curvilinear form, struck with a radius of half the length of the general radius of the wheel, and corresponding, in position, length, and curvature, to the pressing portions *e* of the rotating platen F. This construction is more clearly exhibited in fig. 3 of the drawing, where *f* represents the general centres and *g* the general pitch lines of the wheels; *h*, the centre, and *i* the pitch line of the quicker curvatures of the wheel G, corresponding to the pressing portions *e* of the platen F; and *j* the centre or pitch line of the straight-rack constructions of the wheel H, corresponding to the type-holding or form surfaces *d* of the rotary bed I. The surfaces *d* and *e* may be of varied length and width, according to the work required to be done by the press, and there may be a greater or less number of such surfaces outside of or around the axial of the bed and platen, or a number of beds and platens arranged side by side on the shafts *b* and *c*, with their form and pressing surfaces differently pitched, the driving gear being arranged to correspond. The principle of action, however, is illustrated by the arrangement shown in the drawing. Thus, while both the type-bed and platen rotate, or, it may be, only partially rotate, and then repeat the action, I am enabled to use a straight form to or on the type-bed, and thus dispense with a special construction of type or wedge-shaped type furniture to secure a cylinder-press action, the straight type-holding portions *d* of the bed and quickened curvatures *e* of the platen relatively to the circle in which the latter at its extreme point moves and travels in unison with the bed and platen, as described, by the gears G and H, as constructed, or other equivalent means, securing a correct and regular impression, free from slipping of the sheet passed in between the bed and platen. A pressing curvature of the platen, corresponding to the general pitch line of its driver, and other than straight or rack-construction to the driver of the type-bed, would necessarily produce an irregular impression and slipping of the sheet. The advantage of using ordinary type or type-furniture for cylinder-press action, irrespective of the diameter of the cylinder or cylinders, will be readily seen, and needs no further comment. J is the

inking-roll, made of ordinary or any other suitable composition, and hung on a shaft, *k*, the ends of which are left free to play in slots *l* of the frame, and which shaft is drawn inwards by springs *m*, to keep said roll up to its work against the form, when the latter, in the rotation of the bed, comes round to be inked; disks *K*, on the bed-shaft, having flattened portions, *n*, corresponding to the form, serving, in connection with taper rollers *L* on the inking-roll shaft and the springs *m*, to give to the inking-roll its proper action relatively to and on the form; but, instead of, as is usually done, to provide for shrinkage of the inking-roll, keeping a change of rollers of different diameters for the disks *K* to act against, or altering the bearings of the rollers, both of which are inconvenient and otherwise objectionable, I provide for such shrinkage by simply sliding the taper rollers *L* on the inking-roll shaft, hung and controlled by springs, as described, so as to vary their diameters where they come in contact with the disks, and when properly adjusted securing them, say, by keys or otherwise.

What I claim as my invention, and desire to secure by Letters Patent, is—

The combination of the adjustable or sliding taper rollers *L*, with inking-roll shaft *k*, hung and controlled essentially as described, and disks *K*, for operation together, substantially as and for the purpose or purposes herein set forth.

EDWIN ALLEN.
